UNITED STATES PATENT OFFICE.

ROBERT SHEDENHELM, OF GRINNELL, IOWA.

POWER-OPERATED MATERIAL LOADING, CONVEYING, AND DISCHARGING MACHINE.

Application filed September 27, 1921. Serial No. 503,643.

My invention relates to that class of material loading, conveying and discharging mechanism as illustrated in my Patent Number 1,226,125, issued May 15, 1917, on a manure loader.

The object of my present invention is to provide for operating a machine of this kind by power from an engine; and more specifically it is my object to so arrange and combine the engine supporting frame with the machine for loading, conveying and discharging material that it will permit the loading, conveying and discharging machine to be operated in certain positions and under certain conditions in which it could not successfully operate when being advanced by draft animals or by an independent tractor.

Another object is to provide simple, durable and inexpensive driving and controlling connections between the engine and the several parts of the material loading, conveying and discharging machine whereby the machine may be advanced and the various operative parts of it driven either independently or in unison, or whereby said parts may be driven independently or collectively while the machine is standing still, or whereby, when the machine is being advanced the loading conveyor may be operated at different speeds relative to the speed of advance of the machine, and whereby all of the ordinary functions of said loading, conveying and discharging mechanism may be performed in a convenient, facile and economical manner.

My invention consists in the combination of a material loading, conveying and discharging mechanism of the class described of an engine supporting frame arranged at the side thereof and capable of independent rocking movement centered on the main axle, and in the construction, arrangement and combination of the gearing and controlling devices from the engine to the machine advancing mechanism, whereby the objects contemplated are attained, as herein-after more fully set forth, pointed out in my claims, and illustrated in the accompanying drawings, in which:

Figure 1 shows a top or plan view of a de-

vice embodying my invention with parts broken away showing certain structural details.

Figure 2 shows a side elevation of the same.

Figure 3 shows an enlarged, detail sectional view illustrating the driving connections between the engine shaft and the main axle, and also between the engine shaft and the driving mechanism of the material loading, conveying and discharging machine.

Referring to the accompanying drawings, I shall first describe the material loading, conveying and discharging machine.

In this connection, however, it should be understood that I have not in the application attempted to fully illustrate and describe the details of this machine, for the reason that it of itself forms no part of my present invention, and I have only herein illustrated and shall describe the essential parts thereof, and I hereby refer to the aforesaid Patent No. 1,226,125, issued May 15, 1917, for the detail drawings and description of said machine.

The machine comprises a main frame indicated generally by the numeral 10. At its forward end are the steering wheels 11 mounted on stub axles and controlled by the crank wheels 12 connected by a sprocket chain 12^a through a steering mechanism hereinafter described.

Within the frame there is a wagon bed indicated generally by the numeral 13. This wagon bed is capable of up and down tilting movement centered on the main axle. At the forward end of the wagon bed is a loading conveyor indicated generally by the numeral 14, and provided with an earth cutting blade 15 at its front end. In the bottom of the wagon bed is a slatted apron 16, and independent means are provided for driving the elevating conveyor at the front and the slatted apron in the wagon bed, as will be hereinafter more fully disclosed in connection with the description of the gearing mechanism.

The means for raising and lowering the front end of the wagon bed relative to the frame 10 comprises a hand wheel 17 located

conveniently accessible to the driver's seat, and operatively connected to a shaft 18 through the beveled gears 19 and 20. A worm gear 21 is mounted on the front of the shaft 18 and is in mesh with a worm gear 22 on a cross shaft 23, which has its bearings in the frame 10. This cross shaft 23 has pinions 24 fixed to it, which in turn are in mesh with the vertical racks 25, the lower ends 10 of which are attached to the frame at the forward end of the elevating conveyor.

In practical use with this material loading, conveying and discharging machine, the earth cutting blade at the front is moved 15 downwardly by manipulation of the hand wheel 17 until it can cut to the desired depth into the earth's surface, over which it is being advanced. Then as the machine is advanced, the material is carried up and deposited 20 in the front of the slatted apron in the wagon bed, and when it is piled up high enough within the front end of the wagon box, the slatted apron is advanced a slight distance toward the rear, thus giving room 25 for more material to be piled in the front of the wagon box. This operation continues until the wagon box is filled, then the machine is transported to the point of discharge after elevating the front end of the 30 wagon box, and when at the point of discharge, the slatted apron is moved to discharge the material from the rear end of the wagon box.

To provide for causing the said material 35 loading, conveying and discharging machine to perform all of its important functions by power from an engine associated with the machine, I have provided a device in the nature of an attachment to support the engine, and to operatively connect it with the 40 various parts of the material loading, conveying and discharging machine.

This attachment comprises a main axle 26 45 rotatably mounted in suitable bearings on the frame 10 and extended beyond both sides of it. Fixed to one end of the axle 26 is a drive wheel 27, and rotatably mounted on the other end of it is a sleeve 28, and a traction wheel 29 is fixed to this sleeve 28. Rotatably mounted upon the axle 26 is a beveled gear 29^a, which is driven from the engine in the manner hereinafter described, and which may be connected by a clutch 30 with the said axle 26.

A differential gear of the ordinary construction is provided and indicated generally 55 by the reference numeral 31, its large pinion on one side being fixed to the main axle 26, and its large pinion on the other side being fixed to the sleeve 28, and when thus arranged it performs the ordinary function of a differential gear in applying driving power to both of the traction wheels at the same time, and yet permits one of 60 them to move independently of the other.

In this connection, however, I wish to call attention to the fact that the main axle 26 is fixed to one drive wheel and extends through and beyond the other.

I also wish to call attention to the fact 70 that the rear end of the frame 10 is supported on this main axle, and also that the wagon box is mounted on it in such a manner that it may tilt vertically about a point centered on the main axle. 75

The engine supporting frame is indicated generally by the reference numeral 32. At its rear end are the bearings 33, by which it is pivotally supported on the main axle on the opposite side of the traction wheel 29. 80 At the front of the frame 32 is a supporting castor wheel 34.

The engine is indicated generally by the reference numeral 35, and is preferably mounted at the forward end of the engine 85 frame 32. Extending rearwardly from it is the engine shaft 36, on which there is a driving pinion 37.

For transmitting power from the engine to the beveled pinion 29^a, I have provided a 90 shaft 38 mounted in suitable bearings in the engine frame 32, and provided at its forward end with a pinion 39 loosely mounted and in mesh with the pinion 37, and on its rear end with a beveled pinion 40 fixed to the shaft 38 and in mesh with the pinion 29^a. A clutch 41 is provided for operatively connecting the pinion 39 with the shaft 38. 95

Rotatably mounted on the shaft 38 is a 100 sleeve 42 having at its forward end a clutch 43 by which it may be operatively connected with the pinion 39 for driving the sleeve, and on the rear end of the sleeve 42 is a beveled pinion 44. This latter pinion is in mesh with a large beveled gear wheel 45 105 connected with a hub portion 45^a rotatably mounted on the axle 26. The small pinions 45^b of the differential gear are carried by this gear wheel 45. On the other side of the drive wheel 29 is a corresponding large beveled gear wheel 46, and this wheel 46 is arranged to be driven from the engine at times, as follows:

The numeral 49 indicates a driving shaft 110 having loosely mounted at its forward end a gear wheel 50 in mesh with the engine shaft gear 37, and at its rear end is a beveled pinion 51 fixed to the shaft 49 and in mesh with the large beveled gear wheel 46 on the main drive wheel 29. A clutch 52 is provided for operatively connecting the pinion 50 with the shaft 49. 115

In this connection, I have provided means whereby when one of the pinions 44 and 51 is in operative connection with its corresponding large beveled wheel on the main drive wheel, the other will be operatively disconnected therefrom as follows:

The numeral 53 indicates a lever fastened to the frame 32 and having at each end a 130

link 54. These links are in turn pivoted to the central portion of one of two levers 55. The outer ends of said levers being connected respectively to the clutches 43 and 52, 5 and their inner ends being pivoted to the frame 32. As shown in Figure 1, both of the clutches 43 and 52 are disengaged. From this position and when the lever 53 is moved in one direction, the clutch 52 will be thrown 10 into engagement, and when the lever 53 is moved in the opposite direction the clutch 43 will be thrown into engagement.

I have provided for driving the slatted apron in the wagon box and the elevating conveyor in the front of the wagon box, either separately or jointly as desired, by power from the engine, and when the wagon box is in any position of its adjustment as follows:

20 Extended rearwardly from the main axle is a shaft 56 having a sliding non-rotatable sleeve 56^a on which there are two beveled pinions 57 and 58 designed to coact with the pinion 59 on the shaft 60 which operates 25 the slatted apron 16. A sleeve shifting device 61 is provided for operatively connecting either one of the beveled gear wheels 57 and 58 with the pinion 59, or to disconnect both pinions 57 and 58, and this device 61 30 is controlled by a lever 62 located in position where it is convenient to the operator. A beveled pinion 57^a is fixed to the front end of the shaft 56 in mesh with the pinion 29^a.

35 As before explained, the beveled gear wheel 29^a may be operated by the engine either when the machine is stationary or when moving, and hence the slatted apron may be operated in either direction any time 40 when the engine is running, regardless of the movement of the machine.

For operating the elevating conveyor, I have provided a shaft 63 having a pinion 64 at its rear in mesh with the pinion 65 loose 45 on the shaft 56. A clutch 66 is provided by which the pinion 65 may be operatively connected with the shaft 56, and this clutch is controlled by a lever 67 arranged conveniently accessible to the operator. At the forward end of the shaft 63 is a small beveled pinion 68 in mesh with the pinion 69 on a shaft 70 of the elevating conveyor.

By this arrangement, the elevating conveyor may be operated any time regardless 55 of the operation of the slatted apron or of the advance of the machine.

From the construction heretofore described, it is obvious that it is possible to rotate the main axle 26 either through the 60 gears 44 and 45 or through the gears 40 and 29^a; and thereby either advance or back the machine.

Further in this connection, attention is called to the fact, that assuming the motor

is running at uniform speed, it is possible 65 with my improvement to vary the speed at which the machine is advanced relative to the speed at which the elevating conveyor may be driven to meet the requirements of practical use, and in this connection it may 70 be explained that when operating in loose material, such as for instance sand or gravel, it is desirable to have the elevating conveyor run at relatively high speed to the advance 75 of the machine, and when working in material such as, for instance wet clay, it is desirable that the speed of the elevating conveyor be substantially the same as the speed of the advance of the machine. I accomplish this desirable result as follows:

80 It will be noted that the gear wheel 29^a, through which the elevating conveyor is operated, is loose on the main axle, but may be clutched to the main drive axle.

Furthermore, it will be noted that the 85 beveled pinion 44 is rotatable on the drive shaft 38, and that it may be driven when the drive shaft 38 is idle.

The pinion 39, as before explained, is 90 geared to the engine and runs at all times when the pinion 37 is running, and that this pinion 39 may operate to advance the machine through the sleeve 42 and the gears 44 and 45.

95 I have provided means whereby the operator may cause the clutch 41 to be thrown into engagement, and the clutch 30 will be thrown out of engagement at the same time, or upon an opposite movement, the clutch 41 to be thrown out of engagement and the clutch 30 to be thrown into engagement. This means comprises a connecting rod 41^a 100 attached to the lever 41^b that is connected to the clutch 41, and also this rod 41^a is extended rearwardly to where it is connected to a bell crank lever 41^c, which in turn is 105 connected to the clutch 30.

110 By this arrangement, it will be seen that when the clutch 30 is out and the clutch 41 is in, then power is transmitted from the engine to the bevel pinion 29^a through the shaft 38, and by reason of the relative sizes of the gears, the pinion 29^a will be driven relatively slow, hence the elevating apron will run comparatively slow, at the same time the machine is advanced through the sleeve 42 and the pinions 44 and 45, assuming, of course, that the sleeve 42 is clutched to the pinion 39. Then if it should be desired to 115 run the elevating conveyor relatively fast, the clutch 41 is moved away from the pinion 39, and the clutch 30 is thrown into engagement with the pinion 29^a. When this is done, the shaft 38 is idle, but the sleeve 42 drives the gear wheels 44 and 45 and the

120 large beveled pinion 29^a is driven from the large beveled pinion 45 through the differential and the axle 26, so that it goes at a 125

higher rate of speed relative to the advance of the machine, than when driven through the shaft 38.

For operating the steering wheels 11, I 5 preferably provide a steering wheel 71 and two cables 72 connected with the steering wheel and passed around a suitable guide pulley 73 and connected with the crank wheels 12, the operation of these parts being 10 well known, no further detailed description is necessary.

In practical use my improved machine is intended principally for such work as road grading, cellar excavating, manure handling and so forth.

For instance, in cellar excavating, the elevating conveyor and the cutter at the front thereof are lowered to operative position, and then the machine is advanced to a point 20 in line with one edge of the cellar to be excavated. Then the machine can be turned around in a small space and its load of earth may be carried to a point of discharge.

In work of this kind my machine has an 25 advantage in that the cutting blade and the elevating conveyor may be moved to position against a vertical wall of earth, and the elevation conveyor can be operated after the machine has stopped its advance.

30 Machines of this kind are very frequently required to advance over very rough and uneven surfaces, and my arrangement of having the main frame, the engine frame and the wagon box all capable of independent 35 up and down movement centered at the main axle, provides a machine that can be very easily adapted to uneven road surfaces without strain or injury to the machine.

By locating the engine in front of and in 40 line with the main drive wheel, I am able to employ a very simple and inexpensive gearing mechanism, and one that will drive both drive wheels in the ordinary manner through a differential gear.

45 In addition to this, the main drive wheel may be directly driven either forwardly or rearwardly, while the other drive wheel is held stationary so that the machine may be turned around in a very small space centered 50 upon the stationary drive wheel.

Considered aside from its function as a material loading, conveying and discharging machine, my improved device provides a 55 general purpose tractor. With the wagon bed in its normal position, and the elevating and discharging mechanism out of gear, the device may be used for all of the purposes for which an ordinary tractor is now used. Ordinarily when in use for such purposes

60 as plowing and the like, the wagon box is empty and the tractor as a whole weighs substantially the same as other tractors. However, there are some instances when it is desirable to increase the weight of the 65 tractor for the purpose of getting additional

traction on the drive wheels for the purpose of pulling a heavier load, and when such condition presents itself, it is a very easy matter with my improved machine to fill up the wagon bed with earth or other material, and thus greatly add to the weight of the tractor, and thereby obtain more tractive power.

I claim as my invention:

1. In a device of the class described, the 75 combination of a main frame, an engine frame arranged at the side of the main frame, a supporting axle, the rear portion of each frame being pivotally supported on the said axle so that each frame may 80 have independent up and down movement centered at said main axle, steering wheels for the front end of one of said frames, a caster wheel for the front end of the other frame, gearing devices operatively connected with said axle for transmitting power from it to various parts of the main frame, a traction wheel fixed to said axle, a second traction wheel rotatively mounted on the axle, an engine carried by the engine frame, and means for transmitting power direct from the engine to the rear axle or to the traction wheel rotatively mounted on the rear axle.

2. In a device of the class described, the 95 combination of a main frame, an engine supporting frame arranged at the side of the main frame, a main axle upon which both frames are mounted, two traction wheels mounted upon said axle, one being fixed thereto and the other being rotatable thereon, an engine mounted on the engine frame, gearing devices between the engine and the traction wheels whereby the latter may be 100 driven by power from the engine, a differential gearing device between the said axle and the traction wheel that is rotatable on the axle, steering wheels for the front end of the main frame, and a caster wheel for the front end of the engine frame.

3. In a device of the class described, the 110 combination of a main frame, an engine supporting frame arranged at the side of the main frame, a main axle upon which both frames are mounted, two traction wheels 115 mounted upon said axle, one being fixed thereto and the other being rotatable thereon, an engine mounted on the engine frame, and gearing devices between the engine and the traction wheels whereby the latter may be 120 driven by power from the engine, a differential gearing device between the said axle and the traction wheel that is rotatable on the axle, for the purpose as stated.

4. In a device of the class described, the 125 combination of a main frame, an engine supporting frame arranged at the side of the main frame, a main axle upon which both frames are mounted two traction wheels mounted upon said axle, one being fixed 130

thereto and the other being rotatable thereon, an engine mounted on the engine frame, and gearing devices between the engine and the traction wheels whereby the latter may be driven by power from the engine, a differential gearing device between the said axle and the traction wheels that is rotatable on the axle, two large gearing wheels

fixed to opposite sides of the traction wheel that is loose on the axle, and means for operatively connecting one or the other of said gearing wheels with the engine for moving said traction wheel either forwardly or rearwardly without advancing the other traction wheel, for the purpose as stated.

ROBERT SHEDENHELM.
